Blind, 2-Motorized butterfly blinds, one pull lifting motor control, easygoing for your life, as shown in https://www.instagram.com/heyblinds_fabric_manufacturer/reel/DCt1vg2SSjz/, Nov. 23, 2024.

Primary Examiner — Clare Ann Gannon

(74) Attorney, Agent, or Firm — S.J. Intellectual Property LTD.

(57) **CLAIM**

The ornamental design for a blind, as shown and described.

DESCRIPTION

FIG. 1 is a front, left and top perspective view of a blind, showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, left and top perspective view of the blind, shown in a state of use;

FIG. 10 is a rear, right and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines in the figures depict portions of the blind that form no part of the claimed design.
